SET OF GAME PIECES

Robert A. Kenyon II, Boulder, Colo.

Application July 27, 1954, Serial No. 31,630

Term of patent 14 years

(Cl. D34—5)

FIG. 1.

FIG. 3.

FIG. 5.

FIG. 2.

FIG. 4.

FIG. 6.

FIG. 7.

FIG. 10.

FIG. 8.

FIG. 9.

FIG. 11.

FIG. 12.

FIG. 13.

To all whom it may concern:

Be it known that I, Robert A. Kenyon II, a citizen of the United States, residing at Boulder, in the county of Boulder and State of Colorado, have invented a new, original, and ornamental Design for Set of Game Pieces, of which the following is a specification, reference being had to the accompanying drawing, forming a part hereof.

Figures 1 and 2 are, respectively, top plan and front elevational views of a game piece representing a planet;

Figures 3 and 4 are, respectively, top plan and front elevational views of a game piece representing a rocket;

Figures 5 and 6 are, respectively, top plan and front elevational views of a game piece representing an electronic computer;

Figures 7, 8 and 9 are, respectively, top plan, front elevational and side elevational views of a game piece representing a solar agent;

Figures 10 and 11 are, respectively, top plan and front elevational views of a game piece representing an atomic pile; and

Figures 12 and 13 are, respectively, top plan and front elevational views of a game piece representing a guided missile.

I claim:

The ornamental design for a set of game pieces, as shown.
